UNITED STATES PATENT OFFICE.

DON A. McNAUGHTON, OF MARYVILLE, TENNESSEE.

COMBUSTION-INDICATOR.

1,311,905.

Specification of Letters Patent.

Patented Aug. 5, 1919.

Application filed August 17, 1915. Serial No. 46,003.

To all whom it may concern:

Be it known that I, DON A. McNAUGHTON, a citizen of the United States, residing at Maryville, in the county of Blount and State of Tennessee, have invented a new and useful Improvement in Combustion-Indicators, of which the following is a specification, reference being had to the accompanying drawing.

- 10 My improvement relates particularly to indicators for indicating the draft relations in steam boiler furnaces and other furnaces presenting similar conditions or construction.
- 15 The object of the improvement is to provide a simple and efficient apparatus whereby indications of draft conditions in several portions of the furnace may be simultaneously taken in such manner as that
- 20 they may be utilized for correction of conditions and the establishment and maintenance of proper air and fuel ratios tending to afford the best combustion conditions.

The result desired is to transmit to the instrument the pressure conditions at the three principal stages of draft resistance found in the operation of such furnaces, and to oppose such pressures in pairs against opposite ends of oil columns in observation tubes and position said columns with reference to the difference between the pairs of pressures applied thereto, the column moving out of the normal atmospheric position only a distance which is proportional to the difference between said two pressures, this being a movement less than would be the case if normal atmospheric pressure bore against one end of the column and a pressure from one of the furnace spaces were transmitted against the opposite end of said column.

One of these pressure pairs consists of the pressure existing in the damper space (the space in the stack below the damper) and the other consists of the pressure in the combustion space (the space above the grate), and the other pair of pressures consists of the pressure in the combustion chamber and the pressure in the ash-pit space (the space below the grate). The pairing of these last two pressures is of special importance in attaining sensitiveness and range, as will be hereinafter described.

It may be further observed that with these pressures paired in opposition to each other, as above stated, an increase or a decrease

in pressure need not necessarily be indicated on the oil column, only changes in differences in such pressures being indicated and only such indication being desired. If 60 the pressures of either pair increase or decrease proportionally, the position of the corresponding oil column will remain substantially stationary.

Assuming that, in the operation of such a 65 furnace, the thickness of the fuel bed (or the amount of fuel exposed for combustion) with relation to the volume of air supply is such as to result in economical and efficient or so-called complete combustion, 70 there will necessarily exist certain conditions of draft pressures relative to each other at different points within the furnace and the setting.

If this relationship of amount of air supply to fuel is disturbed, the draft pressures will re-arrange their relationship correspondingly and will seek a new equilibrium. The apparatus herein described utilizes the difference in pressures between the pressure in the region of the damper, in the space above the grate surface, and in the space beneath the grates where the pressure is reduced below atmospheric pressure, and these three pressures are equalized in two 80 inclined transparent indicating tubes conveniently located, so that any changes occurring in the relationship of the pressures within the furnace will show in the action of the liquid in the indicating tubes. The 85 character and meaning of changes in pressure will be determined as hereinafter explained.

Under all ordinary conditions of operation, the pressure in the three furnace spaces, 95 the damper space, the combustion space, and the ash-pit space are unequal, and their pressures increase progressively along the course of travel of the air and the products of combustion, the pressure in the ash-pit being relatively low and the pressure in the combustion chamber being higher, and the pressure in the damper space being yet higher. In other words, these spaces are in series relative to the course of gaseous travel, 105 and the pressure of said series increases progressively with travel along said course.

The accompanying drawing shows, a steam boiler and furnace with my improved indicating mechanism applied thereto, said 110 mechanism being shown in elevation.

The furnace is of ordinary form. B is

the boiler. S is the smoke stack. W is the breast wall. G is the grate. A is the ash-pit or space beneath the grate. C is the combustion space above the grate. D is the 5 damper space or space immediately below the damper.

My indicator mechanism deals with the drafts or gas pressures in the spaces A, C, and D.

10 H and I are transparent indicating or observation tubes. The tube, H, has a middle inclined portion, H¹, and a portion, H², rising from the lower end of the portion, H¹, and a portion, H³, rising from the opposite 15 end of the portion, H¹. The tube, K, has a middle inclined portion, K¹, from the lower end of which rises a portion, K², and from the upper end of which inclined portion rises a portion, K³. The tubes, H and I, each contain 20 a quantity of liquid usually oil sufficient to rise into the portions, H² and K², and to suitable points in the inclined portions, H¹ and K¹.

A conducting tube, 1, has one end secured 25 to the upper end of the portion, H², of the tube, H, in such manner as to permit communication between the tube, H and the tube I, and to exclude the outside atmosphere from the observation tube. The other end 30 of the tube, I, opens into the space, D, below the damper, E, of the smoke-stack, S. A similar conducting tube, 2, is similarly connected with the upper end of the arm, K², of the tube, I, and has its opposite end extending 35 into the combustion space, C, said end being open. A similar conducting tube, 3, is similarly connected to the upper end of the arm, K³, of the tube, K, and has its other end extending into the ash-pit space, 40 A, and said end is open. A similar conductor pipe, 4, is similarly connected to the upper end of the arm, H³, of the tube, H, and has its other end tapped into the conducting tube, 2, through which communication 45 is made with the combustion space, C.

Adjacent the inclined portion, K¹, of the indicator or observation tube, K, is an indicator or pointer, J, movable upon a support, 5, which is parallel to the tube portion, K¹. 50 Adjacent the portion, H¹, of the indicator tube, H, is another indicator or pointer, J, supported in the same manner on a support, 5, which is parallel to said portion of said tube. Thus said pointers are movable, independently of each other, upon their supports, so that said pointers may be made to stand opposite different portions of their tubes within the range of the supports, 5.

When the tubes, H and K, are open to the 60 outer atmosphere and they are secured at their chosen inclination, the liquid is introduced until equilibrium is established in each tube with the liquid in the inclined portion of the tube standing at a chosen 65 point, which is to be designated as the zero

or normal atmospheric point for the liquid in the inclined portion of that tube. In the drawings, said points are marked, 0.

Direct communication between said observation tubes and the outer atmosphere is 70 then cut off and only communication through the pipes, 1, 2, 3, and 4 permitted. Fire is then established in the furnace and, by any desired tests, brought to the highest 75 practicable state of efficiency, this resulting in establishing certain relative pressures in the spaces, A, C, and D; and such pressures will, by coöperating as hereinafter described 80 establish the oil columns at certain points in the inclined portions of the indicator tubes. Such positions of the oil columns are then marked by any convenient method or means. The movable pointers, J, already described, serve for this purpose. They are made movable because 85 different furnaces will bring these oil columns to different positions after the instrument has been secured in position and connected and the furnace fired to efficient condition. It is then assumed that the furnace 90 must be so fired and the drafts so maintained as to hold the ends of the oil columns opposite or relative to said pointers. When these pointers or other marks have been placed, they remain unchanged unless at 95 some future time it is deemed desirable to conduct another test firing with a view to correcting the conditions ascertained by the previous test firing.

Then, after the placing and adjustment of 100 the apparatus has been completed as above described, the apparatus is ready for use from day to day without change of the pointers or the zero or normal marks (which are never changed), excepting that from 105 time to time additional oil is inserted, to compensate for evaporation, to keep the oil columns, when exposed only to atmospheric pressure, to the normal points, as will be hereinafter described.

From day to day, while operating the furnace, the fireman observes the inclined portions of the observation tubes to note the positions of the oil columns relative to the pointers. Usually he will aim to so regulate 115 his firing and the damper adjustment as to hold the oil columns at their pointers; but he may also conduct the firing and adjust the damper so as to hold the two oil columns at approximately equal distances from 120 and at the same side of the pointers. For example, if the rate of combustion is increased or decreased above the test rate of combustion, but under such conditions as to maintain efficiency or approximately complete combustion, the two columns may stand at approximately equal distances 125 above or below the pointers.

It has already been stated that there is advantage in applying the ash-pit pressure 130

and the combustion space pressure in opposition to each other on one of the observation tubes instead of pairing combustion space pressure with outside atmosphere pressure. This advantage is two-fold. First, a shorter indicator tube (having the same inclination) may be used than would be the case if outside atmosphere pressure were applied to one end of the tube; and, second, the sensitiveness of the indicator action is increased and the range of pressures which the indicator can deal with is increased.

The use of the longer tube may be avoided by opposing the ash-pit pressure and the combustion chamber pressure to each other on the observation tube, because the difference between these pressures is less than the difference between the outside atmospheric pressure and the combustion space pressure. That greater difference between said atmospheric pressure and combustion space pressure would cause a travel of the oil column through a greater distance.

The reason why the instrument is made more sensitive by the opposing or pairing of the combustion chamber pressure and the ash-pit pressure on the same observation tube is apparently negatived by what is stated in the last paragraph. For, the suggestion naturally presents itself that such an instrument is made more sensitive proportional to the increase of travel of the indicating medium (the oil). But in my improved apparatus the oil column is operated upon by two agents each of which is acted upon and responsive to variations in furnace conditions, whereas when the outside atmospheric pressure and the combustion space pressure are paired or opposed to each other on the tube, only one of said pressures, the combustion space pressure is sensitive to and variable under variations in furnace conditions, the atmospheric pressure remaining constant or undergoing no changes having any relation to condition in the furnace.

Furthermore, while the pressure in the furnace space and in the ash-pit space are both variable under abnormal conditions, they vary oppositely, sometimes from each other and at other times toward each other. The action in either case being to increase the movement of the oil column and to a greater extent than would be the case if the combustion space pressure alone and atmospheric pressure were acting in opposition to each other upon the oil column.

Adjacent each tube and at opposite sides of the pointer, J, on said tube is placed a symbol, the two symbols adjacent one tube being unlike and the pair of symbols at each side of the tube being reversed with reference to the other pair in relation to the tubes and connections as shown; that is to

say, one of said symbols may be a minus sign, as shown in the drawings, while the other is a plus sign, also as shown in the drawings, and the minus sign belonging to one tube being at the right and the minus sign belonging to the other tube being at the left of the corresponding pointer, J. Either of said symbols may be placed at the side of the adjacent pointer to which the oil column moves when there is an insufficient supply of air in the furnace. The minus sign is preferably chosen for this purpose.

Conductor pipes, 1, 2, 3, and 4 are preferably so connected to the ends of the observation tubes as to reverse the symbols of one pair relative to the other pair, as above stated, in order that the two oil columns may move in the same direction under the same change of condition in the furnace.

For the purpose of facilitating temporarily connecting the observation tubes with the atmosphere to permit observing the oil columns relative to the zero points and to replenish the oil in said tubes, a removable plug, P, is placed into one of the upright arms of each of said tubes, and a three-way cut-off valve, V, is placed on each of the conductor tubes, 1, 2, and 3. No such valve is needed on the conductor pipe, 4, because communication with the short arm of the observation tube, H, with the atmosphere is had through the valve, V, which is located on the conductor pipe, 2.

I claim as my invention,

1. In an apparatus of the nature described, the combination with a furnace having a damper space, a combustion space and an ash-pit space, of two observation tubes normally cut off from the outer atmosphere and each containing liquid, conductor tubing connecting one end of one of said tubes with said damper space and conductor tubing connecting one end of the other of said observation tubes with the ash-pit, and conductor tubing connecting the other ends of said observation tubes with the combustion space, substantially as described.

2. In an apparatus of the nature described, the combination with a furnace having a damper space and a combustion space and an ash-pit space, of two observation tubes normally cut off from the outer atmosphere and each containing liquid, conductor tubing connecting one end of one of said tubes with said damper space and conductor tubing connecting one end of the other of said observation tubes with the ash-pit, and conductor tubing connecting the other ends of said observation tubes with the combustion space, and means for temporarily placing said observation tubes into connection with the outer atmosphere, substantially as described.

3. In an apparatus of the nature described,

the combination with a furnace having a damper space and a combustion space and an ash-pit space, of two observation tubes normally cut off from the outer atmosphere and each containing liquid, conductor piping connecting one end of one of said tubes with said damper space and conductor tubing connecting one end of the other of said observation tubes with the ash-pit, and conductor tubing connecting the other ends of said observation tubes with the combustion space, and means for indicating the positions of the liquid columns under test firing substantially as described.

15 4. In an apparatus of the nature described, the combination with a furnace having a

damper space and a combustion space and an ash-pit space all normally differing in pressure, of two observation tubes normally cut off from the outer atmosphere and each containing a liquid, of means connecting one of said tubes with the spaces having the highest and the intermediate pressure, and means for connecting the other of said tubes with the space having the intermediate pressure and the lowest pressure, substantially as described.

In testimony whereof I have signed my name this 6th day of August, in the year one thousand nine hundred and fifteen.

DON A. McNAUGHTON.
